(57) CLAIM

The ornamental design for a charger base for hand-held vacuum cleaner, as shown and described.

DESCRIPTION

FIG. 1 is a front perspective view of a charger base for hand-held vacuum cleaner showing my new design;

FIG. 2 is a left side view of a charger base for hand-held vacuum cleaner according to FIG. 1;

FIG. 3 is a right side view of a charger base for hand-held vacuum cleaner according to FIG. 1;

FIG. 4 is a front view of a charger base for hand-held vacuum cleaner according to FIG. 1;

FIG. 5 is a rear view of a charger base for hand-held vacuum cleaner according to FIG. 1;

FIG. 6 is a top view of a charger base for hand-held vacuum cleaner according to FIG. 1;

FIG. 7 is a bottom view of a charger base for hand-held vacuum cleaner according to FIG. 1; and,

FIG. 8 is a rear perspective view of a charger base for hand-held vacuum cleaner showing my new design.

The broken line showing is included for the purpose of illustrating environmental features and forms no part of the claimed design.
